UNITED STATES PATENT OFFICE

FRANK H. DIVAN, OF MONROE, WISCONSIN

DESIGN FOR A PONY WAGON

Application filed April 25, 1929. Serial No. 31,001. Term of patent 7 years.

To all whom it may concern:

Be it known that I, FRANK H. DIVAN, a citizen of the United States, residing in Monroe, in the county of Green and State of Wisconsin, have invented a new, original, and ornamental Design for a Pony Wagon, of which the following is a specification, reference being had to the accompanying drawing, forming a part thereof, in which:

Figure 1 is a side elevation of a pony wagon, including a fragmentary showing of the tongue, embodying my new design,

I claim:

The ornamental design for a pony wagon, as shown.

Signed at Monroe, in the county of Green, and State of Wisconsin, this 5th day of April, 1929.

FRANK H. DIVAN.
